CLAIM

The ornamental design for a combined lid and display screen portion for a delivery robot, as shown and described.

DESCRIPTION

FIG. 1 is a front perspective view of a combined lid and display screen portion for a delivery robot, shown with the lid in a closed position, showing our new design;

FIG. 2 is a front perspective view thereof with the lid in an open position;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a front perspective view of a combined lid and display screen portion for a delivery robot, shown with the lid in an open position, showing our new design.

The broken lines shown in the drawings are for illustrative purposes only and depict portions that are not a part of the claimed design.
